RADIO TUNING DEVICE

William J. Schnell, Berwyn, Ill.

Application November 20, 1937, Serial No. 175,695

6 Claims. (Cl. 74—10)

This invention relates to a radio tuning device, more particularly of the "automatic" type.

Radio tuning devices of the "automatic" type with which applicant is familiar are of complicated mechanical or electrical structure; are not susceptible of ready adjustment by the user; and are relatively quite expensive; wherefore it has been found impracticable commercially to equip the cheaper and more popular priced radios with such tuning aids. Therefore it is an object of this invention to provide a compact, efficient and readily adjustable tuning device for radio receivers or the like having a minimum number of operative parts.

Applicant's invention further contemplates the provision of an "automatic" tuning device for radio receivers or the like employing inexpensive and easily manufactured elements, which elements may be readily replaced if necessary.

Other and further objects and advantages of the invention will be apparent from the following description when taken in connection with the accompanying drawing in which:

Fig. 1 is a view in perspective of a radio tuning device embodying the invention.

Figs. 2 to 5 are diagrammatic sketches illustrating the principle of operation of the device of Fig. 1.

As shown in the drawing for the purpose of illustration, the radio tuning device 2 comprises a housing 4 having top, bottom, front, back and side walls, certain of which are preferably removable to permit the assembling and ready adjustment of the elements contained therein.

An operating shaft 6 is supported within the housing 4 and journaled in suitable fixed brackets (not shown). One end of the shaft extends outwardly of the housing for connection to the shaft 8 of a tuning condenser 10 of conventional structure. The shaft 6 may be directly coupled to the shaft 8, or it may be coupled thereto by means of a flexible cable in order that the tuning device 2 may control the tuning condenser from a remote point.

A plurality of pulleys 12 is arranged longitudinally on the shaft 6 in longitudinally spaced relation and each of these pulleys is adjustably secured to the shaft by a set screw 14 carried by a collar 16 formed integrally with, or secured to, the pulley. A plurality of operating levers 18 journaled on a fixed shaft or rod 20 within the housing extends outwardly of said housing through vertical slots or openings 22 in the front wall 24.

The shaft 20 extends parallel to the shaft 6

and is fixedly mounted in the walls of the housing or upon suitable brackets (not shown). Each lever 18 is provided with a rearwardly extending end portion 26, to which is secured a spring 28 which urges the lever in a clockwise direction to the position shown in solid lines in Fig. 1, in which position the lever is at the top of the slot 22 in the front wall of the housing. The end of the spring 28 remote from the lever 18 is anchored to the bottom or back wall of the housing. Each lever 18 at its free end outwardly of the housing carries an upstanding finger piece, key or button 30. The buttons 30 may be provided with circular recesses or transparent, detachable caps for receiving indicating disks inscribed with the call letters representing certain desired broadcasting stations. The levers 18 are equal in number to the pulleys 12 and each lever is connected to an associated pulley by a cable, cord, rope or wire 32 passing about the pulley 12 and having its free end tied or otherwise secured to the lever 18, an opening or fastening 34 being provided in the lever 18 for the purpose of facilitating the tying of the free ends of the cable 32 thereto. In order to assure positive operation of the pulleys by the levers 18 and to prevent slippage between the cables 32 and the pulleys, each cable is fastened or clamped at its midpoint to the pulley, as for example by being looped about a screw 36 threaded into the base of the pulley groove. This clamping means may of course be of any other desired form, as for example a bifurcated resilient clamp secured to the periphery of the pulley and extending between the flanges of the pulley to clamp the cable against movement circumferentially of the pulley groove.

Partitions or the like 38 are inserted between each pulley and cable and the next adjacent pulley and cable in order to prevent interference between the cables.

The tuning device having been connected to the tuning condenser 10 of the radio receiver, adjustment of the tuning device is accomplished as follows. The radio receiver is tuned in the customary manner by manual manipulation of the tuning condenser 10 to a desired broadcasting station. A selected lever 18 is then depressed and its associated pulley 12 rotated on the shaft 6 until both flights of the cable 32 become taut, as shown in Fig. 3. In this position the clamp 36 will lie in a vertical plane passing through the axis of the shaft 6 for, as stated heretofore, the clamp 36 is placed at the midpoint of the cable. The set screw 14 is then screwed in to clamp 55

the pulley in this adjusted position. In a similar manner, the radio receiver is tuned successively to other desired broadcasting stations and the remaining levers and associated pulleys successively adjusted as described.

The tuning device having been adjusted, there will exist in each cable, when the levers 18 are in their extreme upper positions, a pair of loops 40 and 42 of varying length relative to each other, depending upon the angular position of its associated clamp 36 relative to the shaft 6. It will, of course, be apparent that the clamps associated with the different cables will occupy different angular positions within an arc of 180 degrees, which is the limit of movement of the condenser 10 and the shafts 6 and 8.

The operation of the tuning device in "automatically" tuning the radio receiver to the stations to which the tuning device has been pre-adjusted, will be apparent from Figs. 2 to 5, which illustrate the pulleys and levers for adjusting the tuning element to its extreme positions. As shown in Figs. 2 and 3, the shaft 6 will be rotated in a clockwise direction to one extreme position upon depression of a lever 18. As shown in Figs. 4 and 5, the shaft 6 will be rotated in a counterclockwise direction from that extreme position to its original extreme position of Fig. 2, upon depression of the lever 18 associated with another cable 32. Other levers 18 will selectively cause rotation of the shaft 6 in like manner to other preadjusted positions. As one lever and cable unit is operated, the relative lengths of the loops 40 and 42 in each cable 32 will be varied corresponding amounts and hence each lever will at all times be operable to cause rotation of the shaft 6 to a predetermined position. Each lever will cause rotation of the shaft in the direction determined by the flight of the cable having the shorter loop 40, and the extent of such rotation will be determined by the difference in the length of this loop and the loop 42.

Although for purposes of explanation and to facilitate an understanding of the operation, the clamps 36 have been stated to be located at the longitudinal midpoints of the cables 32, it will be evident that they need not be so located but that each may be positioned on its cable at a point displaced therefrom a distance equal to one-fourth the circumference of the pulley.

It will be evident that the cables 32 may be connected directly to the shaft 6 by adjustable collars such as shown at 16, in which case the shaft 6 would be relatively enlarged or the cables 32 may be received directly in grooves in the shaft 6 and the adjustment thereof accomplished by manually pulling upon one flight or the other of each cable.

Further modifications and changes may be made without departing from the spirit of the invention, as for example in place of the one-piece pulleys shown in the drawing, split pulleys, the halves of which are resiliently urged toward each other to frictionally clamp the cables in the pulley grooves, may be provided.

Other changes may be made in the form, construction and arrangement of the parts without departing from the spirit of the invention or sacrificing any of its attendant advantages, and the right is hereby reserved to make all such changes as fairly fall within the scope of the following claims.

The invention is hereby claimed as follows:

1. In a tuning device for a radio receiver or

the like, a tuning element, a shaft for operating said element, a plurality of individually operable cables, means operatively connecting said cables to turn with the shaft and at predetermined points spaced angularly about the axis of said shaft in accordance with the tuning positions of the tuning element for desired broadcasting stations, and selectively operable means connected to said cables to cause operation of said shaft to said predetermined tuning positions. 10

2. In a tuning device for a radio receiver or the like, a tuning element, a shaft for operating said element, a plurality of pulleys, a plurality of cables each intermediately associated with a pulley and extending therefrom to form spaced flights, and individually operable means connected to both flights of each cable, said pulleys being individually adjustable about said shaft to predetermine the relative lengths of the flights of each cable whereby the tuning element may be moved to selectable positions to tune the receiver to predetermined broadcast stations. 15

3. In a tuning device for a radio receiver or the like, a tuning element, a shaft for operating said element, a plurality of levers pivoted at fixed points, a plurality of cables each connected to a lever and operatively connected to said shaft in such manner that each cable in the unoperated position of its associated lever is provided with a plurality of loop sections varying relatively in length in accordance with the adjusted position of the shaft, whereby said levers may be selectively operated to adjust said shaft to different predetermined positions to tune the receiver to the selected station. 25

4. In a tuning device for a radio receiver or the like, a tuning element, a shaft for operating said element, a plurality of operating levers pivoted for individual movement about an axis parallel to the axis of said shaft, a plurality of pulleys spaced longitudinally of said shaft and adjustable angularly relative thereto, a plurality of cables each connected to one of said levers and intermediately associated with one of said pulleys, each cable having a pair of freely hanging loops 40 extending between the pulley and its lever, the loop sections in each cable being of relatively different length, and means for selectively operating said levers to cause a selected cable to become taut whereby its associated pulley and the shaft 50 will be rotated in a direction and to a position determined by the original difference in length between the loop sections of said cable. 45

5. In a tuning device for a radio receiver or the like, a tuning element, a shaft for operating said element, a plurality of operating levers pivoted for individual movement in parallel planes about an axis parallel to said shaft, a plurality of pulleys spaced longitudinally of said shaft and rotatably adjustable relative thereto, a plurality 60 of cables each passing about a pulley and connected thereto at its midpoint, each cable being connected at its opposite ends to a lever and having a pair of loop sections extending between the pulley and the lever, the loop sections in each cable being of relatively different length and means for selectively operating said levers to cause a selected cable to become taut whereby its associated pulley and the shaft may be rotated in a direction and to a position determined 65 by the original difference in length between the loop sections of said cable. 70

6. In a tuning device for a radio receiver or the like, a tuning element, a shaft for operating said element, a plurality of depressible levers 75

operable in parallel planes, resilient means for normally urging said levers to an inoperative position, a plurality of pulleys spaced longitudinally of the shaft, a plurality of cables each connected to one of said levers and intermediately associated with one of said pulleys, each cable having a pair of freely hanging loop sections extending between the pulley and its lever when said lever is in its inoperative position, each pulley being

selectively adjustable on the shaft to cause its associated cable to become taut when the receiver is tuned to a desired station and its operating lever is in the depressed position whereby upon selective operation of said levers the receiver will be tuned to any one of a number of desired stations. 5
